FISHING REEL

Walton E. Sparks, Pittsburgh, Pa., and Thomas F. Sarah,
Akron, Ohio, assignors to The Enterprise Manufacturing Company, Akron, Ohio, a corporation of Ohio

Filed Sept. 29, 1960, Ser. No. 62,468

Term of patent 14 years

(Cl. D31—4)

FIG. 1

FIG. 2

FIG. 4

FIG. 1 is a side elevation of a fishing reel embodying our new design, the opposite side being substantially the same except that the crank and casing therefor are omitted.

FIG. 2 is a top plan thereof.

FIG. 3 is a front end elevation thereof.

FIG. 4 is a rear end elevation thereof.

We claim:

The ornamental design for a fishing reel, substantially as shown.
